Philip C. Rowe

United States Patent Office.

PHILIP C. ROWE, OF BOSTON, MASSACHUSETTS.

Letters Patent No. 86,322, dated January 26, 1869.

IMPROVEMENT IN WRENCHES.

The Schedule referred to in these Letters Patent and making part of the same.

To all whom it may concern:

Be it known that I, PHILIP C. ROWE, of Boston, in the county of Suffolk, and State of Massachusetts, have invented certain new and useful Improvements in Wrenches; and I do hereby declare that the following, taken in connection with the drawings which accompany and form part of this specification, is a description of my invention sufficient to enable those skilled in the art to practise it.

The prime object of my invention is the production of a wrench for rotating gas and steam-pipes, round iron, &c., which, while more effective than any other device with which I am acquainted, for a similar purpose, can be easily and quickly changed, by shifting some of its parts into a cutting-device for cutting off pipes and metal cylinders, or into a wrench adapted to rotating polygonal nuts, &c.

In my improved wrench, whether adjusted for use to rotate cylindrical or polygonal bodies, or to cut off cylindrical bodies, the operative parts are made adjustable toward each other, by the rotation of a nut, and then are powerfully forced toward each other by the grasp of the hand, operating through the medium of a bent lever, and it is in said arrangement and combination of parts that my invention mainly consists, the balance of my invention being found in the details of construction and combination hereinafter described and claimed.

Of the drawings—

Figures 1 and 2 are, respectively, side and front elevations of my improved wrench, arranged for use to cut off cylindrical bodies;

Figures 3 and 4 are, respectively, side and front elevations, showing the changes needed to transform the apparatus shown in figs. 1 and 2 into a wrench adapted to rotate polygonal bodies; and

Figure 5 is a front elevation of the piece which is used to transform the apparatus into a pipe-wrench.

The part of my wrench which serves the purpose of the outer jaw of a common monkey-wrench, or of the outer hooked jaw of a pipe-wrench or tongs, is represented by a bar, having a hooked end, *a*, as shown, terminating in a long handle, or tang, on a portion of which screw-threads *b* are formed, between the head *a* and the handle-part *e* of the bar.

The other main member of my apparatus is a bent lever, the short arm *d* of which is slotted, so as to fit over the hooked bar, as shown in the drawing, the lower edge of the arm *d* resting upon the upper end of the nut *e*, or a washer, *f*, thereon, the bent lever being also slightly coupled with the nut *e*, by spring *g*, one end of which is fixed to the long arm *h* of the bent lever, the other end of the spring being bent and entering a groove turned into and around the nut *e*, one function of the spring being to draw down the bent lever away from the hook *a*, when the nut *e* is turned in one direction, the turning of the nut *e* in the other direction carrying the bent lever toward hook *a*. The other

function of the spring *g* is to keep apart the handles by which the apparatus is grasped and turned.

The hook *a* serves as the curved jaw of a pipe-tongs, or of a pipe-cutter, and, when provided with the shoe *j*, answers as the outer jaw of a wrench for turning polygonal bodies.

The short arm *d*, of the bent lever, serves to carry either the cutter *i*, the biting-jaw, *k*, of a pipe-tongs, or the movable jaw, *l*, of a wrench for polygonal bodies, said parts, *i*, *k*, and *l*, all entering interchangeably the slot in the arm *d* of the bent lever, and being pivoted on the pin *m*, which is made easily removable, having on one end a head, and in the other a score, in which the slide-latch *n* engages, to retain the pin in place, the latch being prevented from accidental movement by the action of the screw *o*, through the spring-washer *p*.

Each of the pieces *i*, *k*, and *l*, is provided with a spring, *q*, which, when the piece to which it is attached is pivoted in place upon the pin *m*, bears against the pin *r*, and operates to press the piece against the bar of the hook *a*.

The bent lever *d* turns, or is fulcrumed against or on the piece which is pivoted on pin *m*, and the lower edge of *d* being inclined, the piece carried on pin *m* is forced upward, through a small range of movement, with great power, as the handles are drawn together by the grasp of the hand.

The pipe-wrench jaw *k*, and the pipe-cutter *i*, are each provided with a screw, *s*, by which their position can be adjusted with reference to the centres of the cylindrical bodies to be operated upon.

In operating with the described apparatus, the nut *e* is turned till the piece *i*, *k*, or *l*, is brought as nearly as may be desired into contact with the body to be operated upon, and then the grasp of the hand upon the handles will powerfully force the piece borne on the pin *m* toward the end *a*. If the cutter-piece *i* is used, the cutter will continue to cut, as long as the whole apparatus is turned, till the handles are brought together, and then, if it is desired to continue the cut, the hand-grasp is released, and the nut *e* is turned up, and, by repeating the hand-grasp and the turning-motion, the cutting is continued.

When the pipe-jaw *k* is used, it is adjusted, like the cutter *i*, by manipulation of nut *e* and screw *s*, and then a firm gripe of a pipe or other cylindrical body is obtained, by drawing the handles together by a hand-grasp, and the whole apparatus is turned as much as may be desired.

Where complete revolutions cannot be obtained, the apparatus is turned back, without turning the cylinder located between the jaws, which let go their hold upon the cylinder simply by loosening the hand-grasp, and when the parts are in proper position for again turning the cylinder, it is again gripped by tightening the hand-grasp, and the cylinder is again rotated with the apparatus.

When the apparatus is used as a wrench, with the jaw *l* and piece *j*, on polygonal bodies, such as nuts, it will be seen that they are firmly held, and do not drop out of the grasp of the jaws, as in the case of ordinary wrenches.

I claim the combination of the hooked screw-shanked piece *a b*, with the nut *e* and bent lever *d h*, substantially as and for the purpose described.

Also, in combination with the matter before claimed, the wrench jaw-pieces *l* and *j*, or the pipe-wrench jaw *k*, or the cutter *i*, substantially as and for the purpose described.

Also, the combination, with either of the pieces *i*, *k*, or *l*, of the spring *g*, substantially as and for the purpose specified.

Also, combining with either of the pieces *i* or *k*, the adjusting-screw, substantially as and for the purpose described.

Also, the spring *g*, arranged and operating substantially as described.
